CLAIM

The ornamental design for a mop for washing automobiles, as shown and described.

DESCRIPTION

FIG. 1 is a rear perspective view of a mop for washing automobiles showing my new design;

FIG. 2 is a top plan view thereof;

FIG. 3 is a bottom plan view thereof;

FIG. 4 is a side elevational view thereof, the opposite side being a mirror image; and,

FIG. 5 is a front perspective view thereof.

The handle, which is of a conventional length, is partially shown in FIGS. 1, 2, and 5 and shown broken away in FIG. 4 for ease of illustration only.

FIG. 1

FIG. 2

FIG. 3

FIG. 4

FIG. 5
